UNITED STATES PATENT OFFICE.

WILLIAM ISSITT AND CLIFFORD M. BROWN, OF ENTERPRISE, KANSAS.

GRAIN-DOOR REMOVER.

Application filed June 22, 1922. Serial No. 570,093.

To all whom it may concern:

Be it known that we, WILLIAM ISSITT and CLIFFORD M. BROWN, citizens of the United States, residing at Enterprise, in the county of Dickinson and State of Kansas, have invented certain new and useful Improvements in Grain-Door Removers, of which the following is a specification.

Our invention relates to new and useful devices for removing grain doors from box cars loaded with grain, and one object is to provide a simple, inexpensive and efficient device of this character whereby one man can readily remove such grain doors without damage thereto, so that they may be used repeatedly.

In the usual practice grain doors are generally destroyed in effecting their removal due to the fact that the grain in the car exerts such pressure on said grain doors that the lower door is usually chopped out with an axe to relieve such pressure. This not only results in loss of time of the operator and the expense entailed in replacing the destroyed doors with others, but the chips chopped from the door become mixed with the grain as it runs from the car and often cause trouble at the elevator where the grain is stored.

By the use of our device the above-mentioned objections are overcome as will hereinafter appear, reference being had to the accompanying drawing, in which:

Fig. 1 is a fragmentary perspective view of a car with our device in position for removing the grain door.

Fig. 2 is an enlarged, broken horizontal section on line II—II of Fig. 1.

Fig. 3 is a front elevation of the device.

Fig. 4 is a side elevation of the device.

Fig. 5 is a detail of a pinch bar used in connection with the device.

Referring now in detail to the various parts disclosed by the drawing, A designates a box car having the usual sliding door B at each side.

C designates the grain doors which are usually nailed to the inner sides of the door post D to prevent the grain from spilling out of either of the doorways E when the respective doors B are opened. Usually two or three grain doors C, C' are placed in each doorway E, the number depending on the size of the car and the load of grain therein. The foregoing parts are of ordi-

nary construction and constitute no part of our invention which will now be described in detail.

2 designates a stand which is of sufficient length to reach from the car floor F to a suitable distance above the topmost grain door C. Said stand 2 consists of a pair of standards 4 spaced a slight distance apart and united at their upper and lower ends by a transverse member 6 and a base 8, respectively. The standards 4 consist, preferably, of angle iron in order to obtain the requisite strength and lightness. The base 8 also consists, preferably, of angle iron, while the transverse member 6 may be a flat bar.

Each standard 4 has a vertical row of holes 10, the holes in one standard being opposite the holes in the companion standard to receive a pin or bolt 12 which constitutes a fulcrum for the pinch-bar 14.

In practice the operator opens the door B at the side of the car from which the grain is to be removed. The stand 2 is then so positioned that its base 8 will rest upon the car floor F while one of the standards 4 will bear against the adjacent door post D where it is held by the transverse member 6, one end of which bears against the rear surface of said door post D, as shown best by Fig. 2. The pin or bolt 12 is then positioned in two of the opposed holes in the standards 4 to come approximately on a line with the lower edge of the uppermost grain door C and constitute a fulcrum for the pinch bar 14, the pointed end 16 of which is forced beneath the lower edge of said uppermost grain door C. The handle end of the pinch bar 14 is then forced downwardly to cause said pinch bar 14 to rock upon its fulcrum 12 and raises the adjacent end of the grain door C as disclosed by Fig. 1. A portion of the grain runs out through the opening thus provided and thereby relieves the grain door C of considerable pressure, so that its opposite end can be easily raised with our device as above-described.

After the upper grain door C has been removed the stand 2 is taken away, as the lower grain door C' can be readily removed with the pinch bar 14 by using the car floor F as a fulcrum upon which said pinch-bar 14 is rocked.

The entire operation of removing the grain doors C and C' occupies but little time and is accomplished without damage

so that they may be used repeatedly and thus avoid the expense of providing new grain doors for each car as it is loaded with grain.

5 From the foregoing description it is apparent that we have provided a grain door remover embodying the advantages above pointed out, and while we have shown and described the preferred construction, combination and arrangement of parts, we reserve the right to make such changes as properly fall within the spirit and scope of the appended claim.

Having thus described our invention, 15 what we claim and desire to secure by Letters Patent, is:

A device of the character described consisting of a pair of standards of sufficient length to extend from the threshold of a 20 car-doorway to a point above a grain door

partially closing said doorway, a base uniting the lower ends of said standards, a transverse bar uniting the upper portions of the standards and extending laterally from each side of the same to engage either door jamb, a fulcrum adjustable to different elevations on the standards, and a lever associated with said fulcrum and having a reduced end for insertion beneath the different sections of the grain door to lift said sections vertically when the opposite end of said lever is forced downwardly.

In testimony whereof we affix our signatures, in the presence of two witnesses.

WILLIAM ISSITT.
CLIFFORD M. BROWN.
